UNITED STATES PATENT OFFICE

2,566,095

OIL CIRCUIT BREAKER

Giuseppe Scarpa, Milano, Italy

Application January 22, 1947, Serial No. 723,607
In Italy January 21, 1946Section 1, Public Law 690, August 8, 1946
Patent expires January 21, 1966

6 Claims. (Cl. 200—150)

1

The present invention relates to an oil circuit breaker of the column type wherein, by the use of an improved type of explosion chamber, and of an improved actuating system, a highly effective performance is obtained.

The circuit breaker according to the invention is characterized by a labyrinth chamber having a plurality of small cavities filled with oil and arranged at different levels, and different radial directions in the arc is trapped so as to bring about many radially directed blasts of oil vapors, each extending in only one direction.

According to another embodiment, the circuit operation of the breaker may be mechanically obtained in a very simple way by means of a shaft, levers and appropriate connecting elements.

Further, according to the present invention a movable hollow contact plunger is provided, so that during its downward motion within the lower part of the enclosing tank, which preferably is separated from the upper one through a diaphragm, a jet of oil is produced at the head of said plunger and directed into the explosion chamber, so that it cooperates effectively in extinguishing the arc.

A transformer within the oil filled lower part of the same circuit breaker is also provided, as well as an insulating cylindrical casing protecting all metallic parts under tension.

According to a modified embodiment of the present invention a pantograph device is arranged between the contact plunger and the insulating actuating rod for reducing the stroke and the speed of the operating rod in respect to those of the contact plunger.

Other features will be fully described in the following description which will be best understood together with the accompanying drawings in which:

Fig. 1 is a partial sectional side elevation of a pole of a breaker, according to the present invention;

Figs. 2 and 2a are two cross-sectional views along an axial and a radial plane respectively of the embodiment shown in Fig. 1;

Fig. 3 is a sectional view of a detail of the operating cylinder and of the locking and signaling device;

Fig. 4 is an axial section of another embodiment of the improved breaker according to the invention;

Fig. 5 is a cross-section of another embodiment of the invention, in which the explosion chamber is located at the bottom instead of at the top of the column and

2

Fig. 6 is an axial section of the central part of an embodiment provided with a pantograph device.

In the embodiment illustrated by Figs. 1, 2 and 3, the reference numeral 1 indicates the terminals, 2 the stationary contact, 3 the movable contact, 4 the piston which operates the lifting of said contact, 5 the cylinder into which slides said piston, 6 the stop ring of the movable contact, 7 a latch locking the movable contact 3 in its closed position; 8 the spring which brings about the opening of the breaker whenever latch 7 is disengaged; 9, 10, 11, 12 are the intermediate members for transmitting the movement between latch 7 and the insulating rod 13, which is actuated in order to open the switch of the operating solenoid 14; 15 indicates an insulating tube concentric with rod 13, in which flows the compressed air coming from the reservoir 16, whenever magnet 17 is actuated; 18 indicates a manually operated auxiliary pump for producing pressure in the reservoir before the closing of the breaker in the event that the supply of air from another source should fail; 19 indicates the insulating supporting body of the circuit breaker in which a transformer may be arranged; 20 indicates the insulating body of the breaker proper, 21 the labyrinth chamber having a central hole 25 (Fig. 2) almost equal to the diameter of movable contact 3; 22 is the lower chamber defined by a cylindrical extension or sleeve 23; 24 is a nozzle situated above the explosion chamber 21 and having a diameter much larger than that of the movable contact 3.

Fig. 2 shows, at an enlarged scale, chamber or member 21; in it, reference numeral 25 indicates the holes forming a central boring having a diameter almost equal to that of movable contact 3, 26 are cavities of much larger diameter, coaxial with holes 25; 27 are cavities axially arranged in respect to holes 25 so as to extend tangentially to same, and located one over the other.

Fig. 3 shows the members operating and locking the movable contact. The lower part of the movable contact plunger 3 actuates piston 4, 45 which slides into cylinder 5, and carries a stop ring 6 with which engages latch 7, which holds loaded the compressed opening spring 8. 9 indicates the slidable rod which, actuated by link 10 and lever 11, can force wedge 28 against stud 29 and actuate latch 7 disengaging ring 6, thereby releasing spring 8, so as to rapidly push downward contact stem 3; 30 indicates the compressed air input conduit to cylinder 5 which, operating on piston 4, lifts the contact stem and causes ring 6 to engage with latch 7, which locks the

contact stem in the closed position; 31 indicates a small two armed lever which, when ring 6 is in the latched position, by means of link 32 holds down slideable rod 33, which operates the signal members of the circuit breaker; when contact stem 3 moves downwards spring 34 is allowed to lift upwards slideable rod 33 and to modify the position of the signal members.

The operation of the circuit breaker described above is the following: To close the breaker it is necessary to build up a pressure in reservoir 16 by means of pump 18, or by connecting it to a compressed air distributing system; thereafter magnet valve 17 is actuated by hand or electrically, thereby admitting compressed air to cylinder 5, which acting on piston 4, lifts movable plunger 3 to engage with stationary contact 2 and at the same time, by compressing spring 8, causes ring 6 to engage with latch 7, thereby locking the contacts in their closed position.

To open the circuit breaker, rod 13 is actuated by means of magnet valve 14 or by hand, thus acting through members 12, 11, 10 and 9 on latch 7 and thereby releasing spring 8 which causes dropping of contact stem 3. Thus an arc is started between the upper end of said stem and stationary contact 2; said arc is trapped in the labyrinth chamber 21 where, on account of oil vaporisation, it is subjected to radially directed gas blasts on different levels, and in different radial directions and this facilitates the breaking of the central nondeionized path of the arc zone when the current passes through zero, preventing the restablishing of the arc.

If, the current having reached a critical value, the extinction of the arc does not take place inside the labyrinth chamber, the expanding arc vaporizes the oil contained in chamber 22; the gases contained therein may escape only in a very limited quantity through the axial hole of the labyrinth chamber, due to the high resistance they meet by the reduced section of said hole 25 and to the effect of the radially moving gas blasts, and force the oil to rise through the space external to the labyrinth chamber, and to escape through hole 24 where said oil, directed across the path of the arc causes its extinction at the next passage of the current through zero.

According to the embodiment shown in Fig. 4, the circuit breaker comprises a cylindrical outer sleeve 41 of insulating material insulating the different live parts and constituting at the same time the main body of the breaker.

Said body 41 carries the stationary contact 42 in whose cavity the upper end of the movable plunger 43 is engaged passing through the labyrinth chamber 44. Plunger 43, however, has an axial hole 43', through which flows an oil stream into the explosion chamber 44, when plunger 43 is dropped, the lower oil containing chamber being separated from the upper one by a dividing partition 45.

The movement of plunger 43 is controlled by a shaft 46 on which is mounted a crank 47 connected to plunger 43 by a link 48. It is easy to understand that such an operating mechanism is especially simple and sturdy, and how the arrangement of the hollow plunger 43 produces a jet of cool oil into the explosion chamber, which efficiently cooperates in the extinction of the arc.

In the lower part 49 of the breaker, which also is filled with oil, according to the embodiment shown in Fig. 4, transformer 50 is arranged whose core and windings are completely oil immersed.

The embodiment shown in Fig. 6 is similar to

the preceding one, that is the circuit breaker has again an outer insulating sleeve 51, stationary contact 52, a movable plunger 53 with an axial hole, and a dividing partition 55 between upper and lower part of the breaker. Differently however from the preceding embodiment, plunger 53 is not directly connected to the operating links and levers, but at a certain intermediate point same is replaced by a pantograph system 59 apt to multiply the stroke and speed of the upper end of plunger 53, in relation to the part connected to the operating levers.

The advantages offered by such an arrangement in addition to those already considered above are evident.

The circuit breaker illustrated in Fig. 5 differs only little from those considered before inasmuch as in it the stationary contact 62 is placed at the lower end instead of at the upper end, 20 and above same the labyrinth explosion chamber is arranged through which movable plunger 63, passes guided and actuated by levers 67, 68, 69 and 70, and controlled by shaft 66. On the disks constituting the labyrinth chamber 64 are provided holes 64' adapted to allow the passage of oil and gases and therefore the operation of the chamber. The actuation of plunger 63 takes place at its upper end which, as already stated, is thus guided during its full stroke, avoiding lateral deflections at the end of the opening stroke, under the violent action of the pressure at the inside.

The circuit breaker in this embodiment as well has the arrangement of the line terminals placed 25 respectively at both ends of the circuit breaker body.

As far as its electrical operation is concerned, this circuit breaker is similar to those previously considered and has therefore the same advantages in addition to having a better guided operating rod.

What I claim is:

1. In a circuit breaker with a rod-shaped movable contact, an oil-immersed arc extinguishing member comprising in combination, an elongated central boring having substantially the same diameter as the contact extending through said boring in the closed position of the breaker; a first cavity in the member, said first cavity extending in a first radial direction from said central boring and communicating therewith; and a second cavity in the member, said second cavity being arranged at a different level with respect to said boring from the level of said first cavity and extending in a second radial direction different from the first radial direction from said central boring and communicating therewith, whereby said cavities form together with said central boring a labyrinth passage for the arc which is subdivided into separate portions by said cavities.

2. In a circuit breaker with a rod-shaped movable contact, an oil-immersed arc extinguishing member comprising in combination, an elongated central boring having substantially the same diameter as the contact extending through said boring in the closed position of the breaker; a first cavity in the member, said first cavity extending in a first radial direction from said central boring and communicating therewith; a second cavity in the member, said second cavity being arranged at a different level with respect to said boring from the level of said first cavity and extending in a second radial direction different from the first radial direction from said

central boring and communicating therewith; and a third cavity in the member, said third cavity being arranged at a different level with respect to said boring from the levels of said first and second cavities and extending in a third radial direction different from the first and second radial directions from said central boring and communicating therewith.

3. In a circuit breaker with a rod-shaped movable contact, an oil-immersed arc extinguishing member comprising in combination, an elongated central boring having substantially the same diameter as the contact extending through said boring in the closed position of the breaker; a plurality of substantially circular cavities communicating with the boring and arranged in the member eccentrically with respect to said boring at different levels and in different radial directions, respectively; and a substantially circular cavity having a larger diameter than each of said eccentrically arranged circular cavities and being centered with respect to said boring and communicating therewith, whereby said cavities form together with said central boring a labyrinth passage for the arc which is subdivided into separate portions by said cavities.

4. In a circuit breaker with a rod-shaped movable contact, an oil-immersed arc extinguishing member comprising in combination, an elongated central boring having substantially the same diameter as the contact extending through said boring in the closed position of the breaker; a plurality of substantially circular cavities communicating with the boring and arranged in the member eccentrically with respect to said boring at different levels and in different radial directions, respectively; and two substantially circular cavities having a larger diameter than each of said eccentrically arranged circular cavities and being centered with respect to said boring and communicating therewith, said centered cavities being arranged, respectively, below the level of the lowest and above the level of the highest of said eccentrically arranged circular cavities, whereby said cavities form together with said central boring a labyrinth passage for the arc which is subdivided into separate portions by said cavities.

5. In a circuit breaker with a rod-shaped movable contact, an oil-immersed arc extinguishing member comprising in combination, an elongated central boring having substantially the same diameter as the contact extending through said boring in the closed position of the breaker; a plurality of substantially circular cavities communicating with the boring and arranged in the member eccentrically with respect to said boring at different levels and in different radial directions,

tions, respectively; a substantially circular cavity having a larger diameter than each of said eccentrically arranged circular cavities and being centered with respect to said boring and communicating therewith, whereby said cavities form together with said central boring a labyrinth passage for the arc which is subdivided into separate portions by said cavities; and a cylindrical extension forming part of the member and being arranged at the end of said boring near said centered cavity.

5 6. In a circuit breaker with a rod-shaped movable contact, an oil-immersed arc extinguishing member comprising in combination, an elongated central boring having substantially the same diameter as the contact extending through said boring in the closed position of the breaker; a plurality of substantially circular cavities communicating with the boring and arranged in the member eccentrically with respect to said boring at different levels and in different radial directions, respectively; two substantially circular cavities having a larger diameter than each of said eccentrically arranged circular cavities and being centered with respect to said boring and communicating therewith, said centered cavities being arranged, respectively, below the level of the lowest and above the level of the highest of said eccentrically arranged circular cavities; and a cylindrical extension forming part of the member and being arranged at the end of said boring near said centered cavity arranged below the level of the lowest of said eccentrically arranged circular cavities, whereby said cavities form together with said central boring a labyrinth passage for the arc which is subdivided into separate portions by said cavities.
